US0D1047408S

(12) United States Design Patent (10) Patent No.: US D1,047,408 S
(45) Date of Patent: * Oct. 22, 2024

(54) FASHION ORNAMENT

(71) Applicant: J. Choo Limited, London (GB)

(72) Inventor: Vanessa Rocha, London (GB)

(73) Assignee: J. Choo Limited, London (GB)

() Term: 15 Years

(21) Appl. No.: 29/838,376

(22) Filed: May 12, 2022

(30) Foreign Application Priority Data

Apr. 11, 2022 (EM) 008934558-0007
Apr. 11, 2022 (GB) 6201530
